UNITED STATES PATENT OFFICE.

CHARLES CARD, OF SACKETT, PENNSYLVANIA.

TUBE-SUPPORT FOR OIL-WELLS.

SPECIFICATION forming part of Letters Patent No. 760,682, dated May 24, 1904.

Application filed October 24, 1903. Serial No. 178,895. (No model.)

To all whom it may concern:

Be it known that I, CHARLES CARD, a citizen of the United States, residing at Sackett, in the county of Elk and State of Pennsylvania, have invented a new and useful Tubing-Support for Oil-WellS, of which the following is a specification.

My invention is an improvement in supports for oil-tubing.

10 The object of my invention is to devise means whereby the tubing may be supported at a point far enough below the surface to be out of danger of injury by heat. At present when an oil-derrick is struck by lightning or 15 the well takes fire from any cause the heat so affects the collar of the tubing that by reason of expansion the threads release their hold and the tubing drops into the well, causing a serious loss and resulting in great inconvenience 20 to the operators. My invention overcomes this difficulty by providing a support having no supporting-threads at or adjacent its upper end and extending the lower threaded end a sufficient distance below the surface of the 25 ground so that heat from a burning well at the surface will not affect the threads.

My invention consists of the novel features of construction and combination of parts hereinafter described, particularly pointed out in 30 the claim, and shown in the accompanying drawings, in which—

Figure 1 is a vertical elevation showing my device in position, the intermediate portion of my support being broken out. Fig. 2 is 35 a perspective view of the device detached, an intermediate portion being broken away. Fig. 3 is a perspective view of the supporting-ring. Fig. 4 is a plan view of the device, the wrench being in position; and Fig. 5 is a perspective view of the wrench.

In the drawings, A represents a portion of the derrick-frame or other suitable support, having an opening adapted to receive the tubing of my support. Resting on this frame or

beam A is an iron ring B, also perforated, as 45 shown at B', and having a vertical annular flange B² encircling the marginal portion B³ of the opening B'.

The tubing-support C consists of an upper cylindrical portion C', having on one side a 50 projecting longitudinal shoulder C², and below the vertical shoulder is a horizontal annular shoulder C³, adapted to seat itself valve-like in the seat formed in the ring B by the flange and marginal portion B³. 55

The lower main portion C³ of the tubing-support is a straight hollow tube adapted to fit in the opening in the beam A. The support C has a cylindrical bore extending its entire length, which bore is threaded at its 60 upper end, as shown at C⁴, and the lower end of the tube is exteriorly threaded, as at C⁵.

An interiorly-threaded coupling D is of a sufficient diameter at its upper end to fit over the lower end of the tube C³, and at its lower end the coupling is of a diameter sufficient to receive the upper end of the oil-tubing E.

A wrench F has a curved portion F', adapted to fit over the portion C' of the tubing-support, and a notch F², adapted to fit over the 70 shoulder C². A pipe from a pump may be fitted into the upper threaded end C⁴ of the tubing-support bore. The lower end C⁵ of the portion C³ will be six or more feet under 75 ground and will not be affected by heat on the surface.

Having thus fully described my invention, what I claim as new, and desire to secure by Letters Patent, is—

A device of the kind described comprising 80 a tube having a vertical, longitudinal shoulder at its upper end, a horizontal annular shoulder below the vertical shoulder, and threaded adjacent its lower end.

CHARLES CARD.
